UNITED STATES PATENT OFFICE

2,544,933

GAS NOZZLE WITH MULTIPLE SLOT-TYPE PORTS

William O. Mellies, Chicago, Ill., assignor to International Harvester Company, a corporation of New Jersey

Application August 16, 1947, Serial No. 768,965

3 Claims. (Cl. 158—116)

1

This invention relates to a burner nozzle for gas burners and similar heaters.

Nozzles of this general type disclosed herein have been heretofore known, one example of which is a nozzle comprising a body having a hollow interior and formed with a hollow tapered end provided with slots therein, the purpose of which nozzle is to diffuse gaseous fuel through incoming air so that such fuel will burn properly. Such nozzles find their principal use in soaking pits or other heating furnaces. It was characteristic of prior constructions that the nozzles were subject to warping and cracking because of the various temperatures to which they were subjected, with the result that the replacement of such nozzles necessarily occurred at a very high rate.

The principal object of the present invention is to provide an improved nozzle so constructed as to be unaffected by temperature changes.

Another object is to provide an improved nozzle in which the tapered slotted end is arranged in such a manner that the slotted portions are independent of each other, so that they may have freedom from each other during expansion and contraction as a result of variations in temperature.

Another object is to provide the nozzle with a tool receiving element by means of which the nozzle may be readily removed from the pit or furnace without the necessity of cooling down the pit or furnace.

The foregoing and other desirable objects and features of the invention will become apparent to those skilled in the art as the disclosure of a preferred embodiment of the invention progresses in the following detailed description thereof as supplemented by the accompanying sheet of drawings in which:

Figure 1 is a plan view of the slotted end of the nozzle, a portion of the tool-receiving means being shown in position therein; and

Figure 2 is a transverse sectional view through the nozzle together with the cap and tool-receiving means, there being shown in dot-dash lines a representation of a conventional pipe to which the nozzle is attached.

The nozzle includes a body having a cylindrical portion 10 provided with a hollow interior and having a conical or tapered end portion 11, the base of which is integral or otherwise joined to the cylindrical portion 10 and the vertex of which as at 12 is spaced from the portion 10. The end portion 11 likewise has a hollow interior forming a continuation of the hollow interior of the

2

cylindrical portion 10 and is thus encircled by a conical or tapered wall 13 provided with a plurality of circumferentially spaced fins 14 running lengthwise of portion 11 or, generally speaking, running along the elements of the cone forming the portion 11. The fins project radially outwardly from the surface of the portion 11 and each fin is provided with a slot 15 which communicates exteriorly thereof and which further communicates with the hollow interior of the body. The slots 15 communicate with each other at the vertex end 12 of the tapered portion 11 and thus communicate with an opening 16 formed at such vertex.

The construction thus far described provides an arrangement in which the fins 14 are independent of each other except at their base portions by means of which they are joined to or form the continuation of the cylindrical portion 10. Consequently the fins 14 are free to expand or contract independently of each other in response to variations in temperature. In prior constructions the arrangement was such that the slotted fins or comparable slotted portions were connected at the upper or vertex ends, with the result that the nozzle was subject to considerable warping and cracking.

The improved nozzle further includes a cap 17 having a lower annular lip 18, the inner periphery of which is of a larger diameter than an imaginary circle including the outer upper ends of the fins 14, whereby radial expansion of the fins may occur without interference of the lip 18. The cap 17 is centrally bored or otherwise apertured at 19 to receive means for securing the cap to the nozzle. In the preferred form of the invention illustrated, a securing means forms part of a tool-receiving element in the form of an eye bolt 20, having its eye portion externally of the cap 17 and including a shank 20' which passes loosely through the opening 19 in the cap and the opening 16 at the vertex end of the shank is threaded at 21 to receive a nut 22 at the interior of the nozzle.

The eye-bolt 20 provides means that may be engaged by a hook or similar tool for the purpose of withdrawing the nozzle axially upwardly from the pipe with which it is associated, such pipe being represented by dot-dash lines in the drawing and designated by the numeral 23. By this means the nozzle may be withdrawn from the pipe 23 without requiring that the furnace or pit be shut down and cooled.

It will be seen from the foregoing description that the nozzle forming the subject of the present

invention is considerably improved over nozzles as heretofore known. The present construction, in addition to eliminating or minimizing the possibility of warping and cracking, also provides novel means for contributing toward the easy removal of the nozzle from its position in a pit or furnace. Other advantages and features of the invention will undoubtedly occur to those skilled in the art, as will various modifications and alterations in the construction and design thereof as illustrated. It is not desired that the invention be limited to the precise details shown and described.

What is claimed is:

1. A burner nozzle or the like, comprising: a body having a hollow interior and including a generally cylindrical part provided with a coaxial, conical end; means providing an axially directed opening at the vertex of the conical end in communication with the hollow interior of the body; a plurality of circumferentially spaced fins running lengthwise on the outer surface of the conical end; and means providing a plurality of slits circumferentially spaced and extending lengthwise of the conical end and being open to provide for communication with the hollow interior of the body, certain of the slots being in communication with the aforesaid opening whereby the vertex ends of certain of the fin-carrying portions of the conical end are separate from each other and free to expand and contract independently of each other.

2. A burner nozzle or the like comprising: a body having a hollow interior and including a tapered end; means providing an axially directed opening at the vertex of the tapered end in communication with the hollow interior of the body; and a plurality of fins circumferentially spaced about and running lengthwise of the tapered end, each fin having a slot running lengthwise thereof and each slot opening to the hollow interior of the body and communicating with the aforesaid opening at the vertex of the tapered end whereby the vertex ends of the fins are separate from

each other for independent freedom for expansion and contraction.

3. A burner nozzle or the like, comprising a body having a hollow interior and including a generally cylindrical part provided with a coaxial, conical end; means providing an axially directed opening at the vertex of the conical end, the opening being in communication with the hollow interior of the body, a plurality of fins circumferentially spaced projecting outwardly of the body and running lengthwise of the conical end, each fin having a slot running lengthwise thereof and each slot opening to the hollow interior of the body and communicating with the aforesaid opening at the vertex of the conical end, whereby the vertex ends of the fins are separate from each other, a cap supported on the conical end of the body at the vertex thereof for covering the vertex ends of the fins, said cap having an opening in axial alignment with the vertex opening, and means for removably clamping said cap to the conical end including a tool receiving portion external to the cap and a shank connected to said portion and to said body, said shank extending through said opening in the cap and into said vertex opening, and being of substantially less cross sectional dimension than said opening whereby the fins are free to expand and contract independently with respect to each other and independently with respect to the shank of the clamping means.
